CARTON STITCHING MACHINE

Arthur S. Morrow, Vancouver, British Columbia,
Canada

Application January 8, 1940, Serial No. 312,921

9 Claims. (Cl. 1-11)

My invention relates to improvements in carton stitching machines. The object of the invention is to provide improvements to single stitch stitching machines whereby the machine may be set to apply any predetermined number of stitches to a carton at properly spaced intervals, to discharge the carton from under the stitcher head and to stop the stitcher head immediately following the placement of said stitches. A further important object is to provide means whereby tie stitches at the ends of each row of stitches can be applied in alignment with the row and also be applied with a stitching machine having only one stitching head. A further object is to provide means whereby the machine can be altered with little time and effort to change the number of stitches to be applied to a fold or carton.

The invention consists of a stitcher having a stitcher head driven by a source of continuous power, means for moving the work under the stitcher after each stitch is made and devices for operating the stitcher head to apply a predetermined number of stitches before coming to rest, as will be more fully described in the following specification and shown in the accompanying drawings, in which—

Fig. 1 is a side elevational view of the invention showing the stitch timing cam.

Fig. 2 is a side elevational view showing the feed and cam driving train.

Fig. 3 is a rear view.

Fig. 4 is a plan view of the work table with the stitcher head omitted.

Fig. 5 is a plan view of the eccentric shaft taken on the line 5—5 of Figure 1.

Fig. 6 is a plan view of the cam shaft taken on the line 6—6 of Figure 3.

Fig. 7 is a sectional view of the eccentric shaft brake assembly taken on the line 7—7 of Figure 6.

Fig. 8 is an enlarged front view of the feed arm.

Fig. 9 is a detail showing the stitcher head driven gear and stitcher shaft with the primary drive pulley and gear to the invention.

Fig. 10 is a detail view of the stitch timing cam.

In the drawings like characters of reference indicate corresponding parts in each figure.

The numeral 1 indicates a frame consisting of vertical supports 2, connecting longitudinal members 3 and 4 and a work table 5 which overhangs one side as shown in Figures 3 and 4. The frame 1 is formed around the pedestal 6 of a stitcher generally indicated by the numeral 7. The pedestal 6 supports an arm 8, see Figures 1 and 4, having at its outer end a stitcher head 9

shown in outline only in Figures 1 and 4, as this may be of any type. At the inner end of the arm 8 a motor 10 is provided which is normally continuously running and which is adapted to drive the stitcher head 9 through a suitable clutch, not shown, and a gear 11. The gear 11, obviously continuously rotating with the motor, has its hub 12 freely journalled upon the stitcher head shaft 13. A trip rod 14, see Figure 9, connects the clutch to enable the drive to be imparted from the gear 11 to the stitcher head shaft. The trip rod is connected by a bell crank 14A and a rod 14B, see Figure 9, to a pedal 15 placed at the base of the frame 1 adjacent the operator's position. As the trip rod is pressed downwardly the clutch engages by spring action and causes the stitcher head shaft 13 to rotate one complete turn, when the trip 14 and the pedal 15 move upwardly by spring action to disengage the clutch. The stitcher mechanism thus far described is of the existing machine to which the contemplated improvements are attached.

Secured to the hub 12 of the continuously rotating gear 11 is a pulley 18 connected by a belt 19 to a pulley 20. The pulley 20 is secured to a countershaft 21 which is journalled adjacent one end from an arm 22. The arm 22 is supported above the work table 5 to enable the carton stitched to pass under it. The inner end of the countershaft 21 is fitted with spaced pulleys 23. Between the pulleys 23 and freely journalled upon the shaft is a frame 24 extending towards the stitcher head in the free end of which a shaft 25 having corresponding spaced pulleys 26 is journalled. This shaft 25 is also fitted with a feed roll 27. The pulleys 23 and 26 are connected together by V-belts 28, the outer faces of which coat with the feed roll 27 to engage the stitched carton to withdraw it from the machine. Supported from the frame 24 is a stop 29 which is adjusted by any suitable means and is adapted to be engaged by a marginal edge of a box when being put in position under the stitcher head 9. The feed roll 27 and the belts 28 are in contact with the table when the stitcher head is at rest and are raised during the stitching process as will be apparent as the description proceeds.

Supported to the rear of the stitcher arm 8 is a rock shaft 32 having a crank 33 at one end and a forked arm 34 at its opposite end. The arm 34 is connected by links 35 to the frame 24 so that by rocking the shaft 32 through the lever 33 the feed roll 27 may be lowered to contact the carton below it.

Below the table 5 an eccentric shaft 36 is 55

journalled which is fitted at one end with a driven sprocket 37 and a driving sprocket 38. The sprocket 37 is driven through a chain 39 from a sprocket 40 fitted upon the stitcher shaft 13 which as previously stated rotates one revolution only to each stitch made by the stitcher head 9. The sprocket 37 is of the same diameter as the sprocket 40, hence the eccentric shaft 36 rotates also once to each rotation of the stitcher head shaft. Below the eccentric shaft 36 is a cam shaft 42 fitted with a driven sprocket 43 having a ratio of one to seven of the stitcher head shaft. The opposite end of the shaft 42 is provided with a cam 45 which is carried beyond the frame 1 for convenience and consists of seven equal segments as indicated by dotted radial lines in Figure 10, six of these segments have face recesses, the purpose of which will hereinafter appear. Below the cam a bearing 46 is slidably mounted in vertical guides 47, this bearing is provided with a stub shaft 48 upon which an oscillating feed arm 49, see detail in Figure 8, and a cam roller 50 are mounted. The feed arm 49 is provided intermediate its length with an opening 51 through which the shaft 42 extends. This opening is large enough to permit the arm to oscillate and move vertically in response to the movement of the cam 45. The upper portion of the cam is provided with a slot 52 and at its upper extremity an arcuate feed shoe 53 is formed, which is adapted to pass through a suitable opening in the table 5 to engage the carton under the stitcher head and press it into engagement with an idler roller 54 mounted below the stitcher head 9 to advance the carton after each stitch is placed. The arm 49 is held up to its work by a pair of suspension springs 55 and is lowered on its return stroke by the cam 45. The shaft 36 is fitted at one end with a variable eccentric 56 of any suitable type having an eccentric roller 59 which engages the sides of the slot 52 of the feed arm 49 to oscillate it.

On the cam shaft 42 a shut off cam 62 is secured, which is provided with one depression only. A rock shaft 63, see Figures 1, 2, 3 and 6 is provided parallel to the cam shaft 42, which is fitted at one end with a cross arm 66 and at the opposite end with a cam arm 67. The cross arm 66 is connected at one end with a vertical rod 68 to the trip rod 14 which on being depressed causes the stitcher shaft 13 to rotate. The cross arm is connected at its opposite end to the arm 33 of the rock shaft 32 by a lift rod 69. The cam arm 67 is fitted with a roller 71 which engages the cam 62 and resides, when the machine is at rest or at the end of its stitching cycle, in the recess of said cam as shown in Figure 7.

Mounted upon the eccentric shaft 36 directly above the cam 62 is a brake 73 having a drum 74 and a normally contracted brake band 75 which is expanded to disengage by a toggle 76. The toggle is rocked by a crank arm 77 through a rod 78 which is connected to the cam arm 67. Since the clutch trip rod 14 is always subject to an upward thrust by a spring within the stitcher pedestal 6 it will be obvious that the roller 71 will be held up in the recess of said cam at all times when the machine is at rest and that the brake 73 will also be applied until the pedal 15 is depressed to depress the trip rod 14 and the vertical rod 68 which is coupled thereto.

The stitcher as initially described is adapted to place one stitch in a carton placed under the stitcher head 9 each time that the pedal 15 is

depressed and the location of each stitch is determined by the operator. The improvements referred to from the numerals 15 et seq. operate as follows:

A carton to be stitched by the machine is after folding placed on the work table 5 and is pushed under the stitcher head 9 until one edge engages the stop 29 which at this time is lowered on to the table 5, thus locating the carton for the first stitch. The pedal 15 is depressed, causing the rod 13 and the rod 63 which is connected to it for simultaneous movement to be drawn downwardly. The lowering of the rod 14 enables the stitcher clutch to be engaged, so that the gear 11 and the stitcher shaft 13 are caused to rotate in unison whereby each complete revolution will apply one stitch. The lowering of the rod 63 through the rock shaft 63 and the cam arm 67 lowers the cam roller 71 out of the depression of the cam 62. The rotation of the shaft 13 imparts rotation to the cam shaft 42, thus rotating the cam 62 and by the time that the first stitch is made the circular peripheral portion of the cam 62 will hold the roller 71 down and keep the rods 14 and 63 depressed until the cam 62 completes its revolution and allows the roller and the two rods to return to normal position of rest, when the stitcher clutch is thrown out and the drive from the motor to the shaft 13 disconnected. With the cam and the gear ratio here shown seven stitches will have been placed at regular time intervals. During the placement of these seven stitches the feed roll 27 and the forward end of the V-belts 28 together with the stop 29 will be held in raised position above the table by the rod 63 and the rock shaft 32 and the forked arm 34, consequently the feed roll, the stop and belts will not influence in any way the movement of the carton being stitched in spite of them being driven continuously from the pulley 19 on the hub 12 of the gear 11. Coincidental with the depression of the pedal 15, the brake 73 will be taken off and as the roller 71 rises again into the depression of the cam 62 the brake will be applied to stop the cam shaft 42 and its cam 62 in the position shown in Figure 1. The rotation of the cam 45 throughout one revolution raises and lowers the bearing 46 as the roller 50 runs into and out of the depressions of said cam. For the purpose of description the raises or crowns on this cam are referred to progressively in order of rotation as A1, A2, A3, A4, A5 and A6, and the depressions as B1, B2, B3, B4, B5 and B6 both inclusive. Obviously as the roller is thrust down the feed arm 49 will be lowered so that its shoe 53 may move towards the front of the machine out of contact with the carton on the table and that as the roller is raised the springs 55 will raise the feed arm that its shoe may urge the carton towards the rear or discharge end of the table. The parts are so timed that the stitches are all placed when crowns of the cam engage the roller 50. The cam on starting has crown A1 on the roller, before the depression B1 reaches the roller the first stitch is placed, B1 being short allows the shoe to be raised for a short time interval only, hence the carton is moved between said shoe and the idler roll 54 a short distance, as the crown A2 depresses the roller another stitch is made and a depression B2 is reached, which is a long depression, the shoe imparting a long movement to the carton, consequently the third stitch is spaced a greater distance from the second than the second is from the first. As each successive depression reaches

40

45

50

55

60

65

70

75

the roller a corresponding movement of the carton takes place until the last depression **B6** is above the roller when a short movement of the carton is made and finally as the crown **A1** rides 5 onto the roller again the seventh stitch is made, which is obviously closer to the sixth than the sixth is to the fifth. The first and last stitch of the line are referred to in the preamble as tie stitches. When the last stitch is made the 10 cam comes to rest through the instrumentalities previously described. Simultaneous with the stopping of the stitching and spacing mechanism, the feed roll **21** will be dropped towards the table **5**, so that the carton now bearing upon a 15 dead roll **79** mounted immediately below the roll **21** will remove the carton from under the stitcher head.

From the above it will be obvious that the tie 20 stitches being placed by a single immovable stitching head must necessarily be in line with the widely spaced stitches of the row.

What I claim as my invention is:

1. In a carton stitcher having a continuously 25 rotating member, a stitcher head normally at rest and a normally stationary trip adapted to be moved to cause the rotating member to actuate the stitcher head to place a stitch in a carton, means for holding the trip in moved position whereby a plurality of stitches are placed progressively, means for moving the carton to space 30 the stitches therein, means for permitting the trip to return to normal position to stop the stitching, continuously running means adapted to engage the carton simultaneously with the 35 return of the trip to normal position to discharge the stitched carton and a stop carried by the discharge means for locating the carton prior to stitching.

2. In a carton stitcher having a single stitching 40 head, a stitcher head shaft, means actuated from the shaft for causing the head to place a predetermined number of stitches without stopping, means for intermittently moving a carton under the stitcher to space the stitches with the first 45 and last stitches being closer to their adjacent stitches than adjacent intermittent stitches, said carton moving means consisting of an arm adapted to engage the carton, means for oscillating the arm and a cam for lowering the arm 50 out of carton engaging position.

3. In a carton stitcher having a stitcher head, means for setting the machine in motion to place a predetermined number of stitches, means for stopping the machine when said stitches are 55 placed, a work table, a feed shoe having reciprocating movement adapted to advance a carton under the stitcher head after a stitch is made, and means for holding the feed shoe in engaging contact with the carton at different time intervals following the placement of some of the 60 stitches by the stitcher head.

4. In a carton stitcher having a stitcher head, means for setting the machine in motion to place a predetermined number of stitches, means for 65 stopping the machine when said stitches are placed, a work table, a feed arm provided with a

feed shoe, said feed shoe being adapted to advance a carton under the stitcher after each stitch is made, said arm being oscillatingly mounted below the table, cam means for lowering the arm and its shoe, and spring means for raising said shoe into contact with a carton being stitched upon the table, said cam being adapted to retract the feed shoe from carton engaging position for different time intervals following the placement of some of the stitches by the stitcher head. 10

5. In a carton stitcher as claimed in claim 4, said cam having a plurality of depressions serving to raise the fulcrum of the feed arm, some of said depressions being longer than others. 15

6. In a carton stitcher comprising a work table, a stitcher head, a stitcher shaft, a continuously rotating member clutch connected to said stitcher shaft to drive it and a trip to disconnect the clutch from the stitcher shaft after 20 the placement of each stitch, a cam for holding the clutch connected through the trip during the placement of a plurality of stitches and to release the trip and disconnect the clutch when said stitches are placed, continuously rotating 25 elements movable above the work table beyond the stitcher head, an operating linkage between the cam and the rotating elements, said cam serving to hold the elements in raised position during the placement of the stitches and to permit said elements to engage the carton to discharge it when said stitches are placed. 30

7. In a carton stitcher having a work table, a stitcher head, a stitcher shaft, a continuously 35 rotating member clutch connected to said stitcher shaft to drive it and a trip to disconnect the clutch after the placement of a predetermined number of stitches and an oscillating arm having a shoe adapted to engage the carton to advance it to space the stitches, and means for moving the arm to vary the duration of carton engagement whereby the spacing between adjacent 40 stitches is varied.

8. In a carton stitcher having a stitcher head, means for setting the machine in motion to place a predetermined number of stitches, means for stopping the machine when said stitches are placed, a work table, a feed arm provided with a feed shoe for engaging the carton to advance it under the stitcher head, said feed shoe being 45 mounted upon a pivot adjacent its base, variable throw means for oscillating the feed arm and its shoe, a cam for lowering the feed arm and means for raising the shoe into engagement with the 50 carton. 55

9. In a carton stitcher having a work table, a stitcher head above the work table, means for feeding a carton under the stitcher head during the stitching operation, and a frame having rotating elements for removing the carton after 60 stitching and a stop carried by said frame adapted to descend into the path of an unstitched carton following the removal of a stitched carton from under the stitcher head. 65
